UNITED STATES PATENT OFFICE.

JACOB REESE, OF PITTSBURG, PENNSYLVANIA.

DEVICE FOR EQUALIZING THE TEMPERATURE OF AND PREPARING INGOTS FOR BLOOMING.

SPECIFICATION forming part of Letters Patent No. 269,233, dated December 19, 1882.

Application filed October 25, 1882. (No model.)

To all whom it may concern:

Be it known that I, JACOB REESE, a citizen of the United States, residing at Pittsburg, in the county of Allegheny and State of Pennsylvania, have invented a new and useful Improvement in Devices for Equalizing the Temperature of Ingots and Preparing Them for the Operation of the Blooming-Mill; and I do hereby declare the following to be a full, clear, and exact description thereof, reference being had to the drawings forming a part thereof.

In the manufacture of steel as commonly practiced by the Bessemer or open-hearth processes the ingots when drawn from the ingot-molds are placed on a car-truck and taken to a furnace and placed therein and heated for one hour or more. When the ingots are considered to be sufficiently heated they are withdrawn one at a time and taken to the blooming-mill and rolled down into blooms. Now, it is a well-known fact that when the ingot is taken out of the ingot-mold, though the ingot is solid on the outside, the inside is in a fluid condition. Consequently the center of the ingot is too hot for blooming, while the outside is too cold.

The object of this invention is to provide means for equalizing the temperature of the ingot by utilizing the heat of its fluid center to raise the temperature of its outside walls, so that the ingot may be taken from the mold in which it is cast and prepared for the blooming-mill without the aid of fuel or any other heat than that contained within itself when the converting-house is located at some distance from the blooming-mill.

Figure 1 is a side elevation of my truck and regenerator with the caps on. Fig. 2 is a side elevation of same through *o o*, shown in Fig. 4. Fig. 3 is a sectional view of same through *x x*. Fig. 4 is a plan view of same with four ingots in and four chambers empty. Fig. 5 is a side elevation of the regenerator and hood in position for heating. Fig. 6 is a cap for closing the regenerator.

In order that others skilled in the art may be enabled to put my invention into practice, I shall now describe the manner of constructing my regenerator.

In Figs. 1, 2, 3, 4, and 5, letters *A* indicate the shell. This shell may be made of wrought-iron or of cast-iron. If made of wrought-iron, it

should be one inch thick and joined together at the corners and at the bottom by angle-iron, riveted or bolted in the usual manner. The 55 axle-lugs *a* should be riveted or bolted to a wrought-iron plate, or, if the shell is made of cast-iron, the lugs may be cast on it. The axles *b* may be made of five (5) and a half inch square steel with journals of four and one-half inches. 60 The wheels shown are four feet in diameter, and may be made so that they will turn on the axle so as to travel freely around curves with but little friction; or, in case of a straight track, the wheels may be tight on the axles, and the 65 axle made round and provided with bearings in the lugs *a*. *b'* is the draw-bar by means of which the car is attached to the locomotive. *c c* are the rails on which the car rests. *e* is the non-conducting lining, and *f* is the chamber or nest into which the ingots are placed to soak. *B* is the hood and pipe for heating up the regenerator previous to charging the ingots.

In the practice of this invention, when the 75 ingots are fourteen inches square at the base and twelve inches at the top, the openings in the regenerator should be fifteen inches square at the top and fifteen inches square at the bottom, or they may be fifteen inches square 80 all the way down. The inner walls should be made of cast-iron or steel of two inches in thickness. When the shell is made it should have an opening of five inches in diameter in its bottom opposite to each opening in the regenerator. A layer of fire-brick of nine inches in thickness should be placed all over the bottom on the inside. In doing this a tile having a five-inch round hole should be placed over each opening in the shell-bottom. When the 90 bottom is thus made, the nest *f* is placed in the shell and a good non-conducting material—such as fire-clay—should be rammed down between the inner walls, *f*, and the walls of the shell *A* until the space is filled and the non-conducting lining *e* is formed. When the regenerator 95 is thus formed, the car is run under the hood *B*, and gas and air let into the hood, and combustion caused to take place over the top of the regenerator. The product of combustion will 100 pass down through the openings and out of the five-inch holes at their base. By this means the cast-iron or steel walls and the lining will become heated. When it has assumed a red tem-

perature the car should be drawn away from the hood, the five-inch openings closed with the stoppers *g*, and sufficient hot sand placed in each mold so as to fill the five-inch openings on a level with the bottom of the molds. The ingots should then be taken from the ingot-molds and dropped in the regenerator, with their bottom or largest ends up, the caps placed over each ingot and all covered with sand or other non-conducting substance, care being taken to exclude the air as far as possible. When the regenerator has been thus filled the car may be taken to any suitable place, and after a space of from twenty to thirty minutes, more or less, according to the initial temperature of the regenerator and ingots, the car may be run up to the blooming-mill and the ingots withdrawn and rolled one at a time, when the ingots will be found to be of a thoroughly uniform temperature of sufficient heat to be rolled in the usual manner. When an ingot is withdrawn to be rolled the cap is immediately placed over the opening and covered, so as to exclude the air from getting in or the heat from passing out. When the regenerator is emptied the car is again run into the converting-house and charged. By this arrangement the regenerator need only be heated on Monday morning, as it will retain sufficient heat so as to be run from the blooming-mill to the converting-house and be refilled without re-heating.

By the use of these devices I am enabled to dispense with the costly method of reheating the ingots and save the great loss by oxidation, and prevent the occasional loss by burning the ingots. In the old method of reheating, cracked rails or seconds are largely due to the great difference of temperature between the outside and the interior of the ingot. When the ingots are taken from the molds they are piled onto a truck and taken to the heating-furnaces. By this method the outside of the ingots become cooled to a large degree by passing through the cold air, and often through the rain, and when placed in the furnace, the center of the ingots being still in a molten state, the high heat of the furnace tends to heat the outside and cause a rapid expansion, and as the inside has already assumed its maximum expansion the outer shell is caused to expand while the interior is contracting, and this tends to crack the outer edges where the difference of temperature is the greatest; and I assume that this cracking of the ingots by the different temperatures of its cross-section is the prime cause of cracked rails or other shapes rolled from ingots. By my improved devices the ingots are taken immediately from the molds and placed in the regenerator. The heat of the metal walls is immediately absorbed by the outer walls of the ingot; then the heat from the fluid center passes outward and heats up the walls of the regenerator, so that the walls

or outer sides of the ingot are not allowed to cool much below the point of solidification, and they are immediately heated by the walls of the regenerator, and the ingot is permitted to cool and contract uniformly, and cracking by differential cooling is avoided.

In forming the regenerator I greatly prefer to construct its inner walls of cast iron or steel, as it is a good conductor of heat, and will give out its heat rapidly to the ingot, and will also take up the heat rapidly which is given off in the molten center solidifying; but they may be made of other metal or equivalent heat-absorbing material, if desired, as a matter of economy.

What I claim as my invention, and wish to secure by Letters Patent, is—

1. A regenerator-car or equalizing-chamber for conveying ingots from the casting-pit to the rolls, consisting of a shell of non-conducting material, having a lining of iron or like heat-absorbing material, substantially as and for the purpose specified.

2. A regenerator car or equalizing-chamber for conveying ingots from the casting-pit to the rolls, said car having a shell of non-conducting material, the interior of which is divided into ingot-cells by partitions of steel or like heat-absorbing material, substantially as and for the purpose specified.

3. A regenerator-car or equalizing-chamber for conveying ingots from the casting-pit to the rolls, said car having a shell of non-conducting material, its interior divided into ingot-cells by heat-absorbing partitions, and a series of stoppers for closing the separate ingot-cells, substantially as and for the purpose specified.

4. A regenerator-car or equalizing-chamber for conveying ingots from the casting-pit to the rolls, having a shell of non-conducting material, the interior of which is divided into cells by a series of partitions, and perforated below opposite the several ingot-cells, substantially as and for the purpose specified.

5. The combination of a movable ingot-regenerator, having an outlet or outlets for the products of combustion, with a fixed hood, *B*, substantially as and for the purpose specified.

6. An ingot-regenerator provided with an open top and bottom, in order that its initial temperature may be secured by forcing hot gases through it, and having lids or caps for closing the bottom opening previous to placing the ingot or ingots in it, and for closing the top after the ingots are put in or taken out, in order that when once heated by the combustion of fuel its temperature may thereafter be kept up by the heat abstracted from the molten centers of the ingots placed in it.
